UNITED STATES PATENT OFFICE

1,991,417

WIPING MECHANISM FOR LASTED UPERS

John Milton Rohrer, Orwigsburg, Pa.

Application December 30, 1931, Serial No. 583,943

21 Claims. (Cl. 12—7)

My invention relates to the manufacture of shoes, slippers and similar articles of footwear, and a particular object of my invention is the production of shoes and other forms of footwear without the application of tacks, or the use of other extraneous holding means for the upper, whether such means pass through the upper into the last or are carried by the latter.

The main object of my present invention is to provide means for wiping down and leveling upon the last, or upon an insole carried by the last, the projecting portion of the upper which extends beyond the last and/or insole after the upper has been pulled over the last, whereby such projecting portion of the upper may be flattened down into condition for the reception of a sole or for further operations upon such turned over and wiped portions before such sole is applied. The wiping operation is effected inwardly and over the insole initially placed on the last.

In carrying out my present invention the pulled-over and lasted upper is placed in a sectional holding mold, portable in character, which may be of the type illustrated in my pending application filed October 9, 1930, Serial No. 487,535, or that illustrated in my applications Serial No. 584,185 and Serial No. 584,186 filed December 31, 1931.

My improved wiping mechanism comprises means for moving wiping elements into and out of proper relative position with respect to the lasted upper disposed in the sectional mold, and means for actuating said wiping elements while positioned over the projecting portion or portions of the pulled-over upper. Such wiping action may be directed inwardly so as to lay the projecting portion of the upper over the insole carried by the last, or directed outwardly so as to level such projecting portion away from the last.

These and other features of my invention are more fully described hereinafter; reference being had to the accompanying drawings, more or less diagrammatic in character, in which:

Figure 1 is a plan view of a suitable table carrying a sectional mold of the portable type; with wiping mechanism within the scope of my invention and operating means for such wiping mechanism disposed at opposite ends of such mold; such mechanism being shown in the inactive position.

Fig. 2 is a view in front elevation of the sectional mold and the wiping mechanism in the position shown in Fig. 1.

Fig. 3 is a plan view similar to Fig. 1, illustrating the position of the wiping elements for the

heel and toe portions of the lasted upper after said elements have been moved to operative position with respect to the lasted upper carried by the sectional mold.

Fig. 4 is a view in front elevation, similar to Fig. 2, showing the wiping elements in the position shown in Fig. 3.

Fig. 5 is a plan view, similar to Figs. 1 and 3, showing the extreme inward position assumed by the wiping elements during a wiping opera-

tion.

Fig. 6 is a cross sectional view taken on the line VI—VI, Fig. 2, looking in the direction of the arrow a, showing an end elevation of the wiping mechanism at the left of the sectional mold.

Fig. 7 is an end elevation of the wiping mechanism at the right of the sectional mold in the position shown in Fig. 5, looking in the direction of the arrow b.

Fig. 8 is an enlarged sectional view of the wiping mechanism at the left side of the machine taken on the line VIII—VIII, Fig. 6, and

Figs. 9 and 10 are detached views illustrating details of my invention.

The sectional mold element, which may be portable in character and serves to support the lasted upper in proper position to have the projecting portion or portions of such upper wiped down upon the insole carried by the last, is shown at 10 in Figs. 1, 2, et seq. Such mold may be detachably or fixedly mounted in or on a table 11 and, if desired, it may be seated in a recess formed in such table. This sectional mold element, preferably of the type shown in the applications before referred to, may comprise a base member 12, having engaging or gripping portions 13, pivotally connected to such base. The upper portions of the gripping members have a contour like that of the last and the upper positioned thereon so as to properly engage and hold the same in the desired position for the wiping operation. In practice I have employed a sectional mold having nine gripping portions or jaw elements; two for the heel portion; one each for the sides, and five for the toe portion of the lasted upper; all as more clearly illustrated in the plan views, Figs. 1 and 3. The sectional mold is shown in the closed position; the clamping means illustrated in my pending applications being omitted. When such clamping means are released the mold may open, and when in the open position it is ready to receive the lasted upper from a portable holder comprising a pulling-over device such as that disclosed in my pending applications before referred to, the operator in-

50
45
35
40
45
50
55

verting this holding device and presenting it to the open sectional mold. After the sectional mold closes against the lasted upper, the portable holder is removed.

5 The sectional mold may be held in the closed position by means of suitable levers pivotally mounted with respect to the table 11; suitable springs being associated with such levers so as to tightly clamp the sections of the mold in the closed position around the lasted upper. This mechanism is more fully disclosed in my co-pending applications before referred to.

As soon as the lasted upper is properly positioned and clamped in the sectional mold and the portable holding device therefor has been released, such lasted upper is ready to have the projecting portion or portions x thereof laid down. The mechanism hereinafter described is designed to wipe and lay down the projecting portion or portions of the upper over the insole y carried by the last upon which the upper is stretched.

15 The improved wiping mechanism forming the subject of my present invention is duplex in character for simultaneous operation upon the heel and toe portions of the lasted upper, and the respective sections or portions of the same are mounted upon the mold-carrying table 11 at opposite ends of the mold 10 supported thereby.

20 In the present instance the sectional mold 10 is arranged between two sets of wiping elements and mechanism to operate the same; each of said wiping elements comprising a pair of blades or jaws carried by a reciprocable frame which may be moved into and out of operative position with respect to the upper mounted in the sectional mold. Each set of blades or jaws is of substantially the same character and construction, and each pair is pivotally connected together so as to be movable as a unit into and out of operative position over the lasted upper, as shown in Fig. 5. After they are so moved provision is made for rocking them back and forth and on their pivotal connections by means carried by the respective supporting frames therefor, and in the present instance such means comprise movable plates reciprocable in guides longitudinally with respect to the frames, and operatively connected to the blades or jaws of the wiping elements; such frames having cam slots operatively arranged with respect to pins carried by the respective blades or jaws so that when the latter are reciprocated with respect to said cam slots, they will be moved over the projecting portion or portions x of the lasted upper and toward and from each other.

25 Provision is made for manually moving the wiping elements into and out of operative position with respect to the lasted upper mounted in the sectional mold 10, with motor-operated means for causing the wiping blades or jaws to move back and forth or rock on their pivotal connection until the projecting portion x of the lasted upper has been fully laid down and held 30 against the insole; the latter having been previously coated with a suitable adhesive or cement. By preference the projecting portion x of the upper has been notched by removing portions of the same, as indicated at z , so that it may be laid 35 down upon the insole without undue wrinkling or overlapping and thereby present a substantially flat surface for the reception of a sole; which wiped portions may or may not be rasped or roughened for the reception of the adhesive 40 or cement designed to hold such sole in position

with respect to the lasted upper and complete the shoe or other article of footwear.

45 In the drawings, I have shown the wiping mechanism as supported by suitable frame-work properly positioned with respect to the sectional mold in which the lasted upper is positioned; the respective frames being indicated at 20 and 21. Each of these frames may comprise a base portion 22, upon which an adjustable support 23 is mounted; the latter being provided with a plurality of guide bearings or supports 24 for a pair of sliding rods 25, carrying a cross-head 26, which in turn supports a rod or shaft 27 carrying the frame which supports the wiping elements. The rod or shaft 27 is arranged to rock in the cross-head 26, and may be operatively connected therewith by means of adjustable collars 28 carried by said rod 27 and held in position by suitable set screws; said collars having rounded faces adjacent the cross-head to facilitate the 50 rocking movement of the rod 27. The frame supporting the wiping jaws is supported in the inactive position by a roller 30 which may be adjustably carried by an arm 31 projecting from the base portion 22, as indicated in Figs. 2 and 4. When these frames are moved so as to bring the wiping elements over the mold, they drop off the rollers 30 and are drawn down so as to bring the wiping elements into engagement with the mold by means of springs 32, in the manner herein- 55 after described.

55 The springs 32 are connected to bell-crank levers 32^a pivoted at 32^b; one arm of such levers being engaged by the frames carrying the wiping elements so that when such frames are moved to bring the wiping elements into operative position over the mold, the bell-crank levers will react upon the springs and cause them to lower the forward ends of said frames. To permit this operation, the rod 40 or shaft 27 supporting the frame carrying the wiper jaws passes through a bearing 33, pivotally supported at 33^a upon a vertically adjustable post 34, which may pass through a guide 34^a carried by the base portion 22, through the table 45 11, and through a bracket member 35 secured to the underside of the latter; such bracket member supporting an adjusting nut 36. By this means the post 34 carrying the bearing 33 may be vertically adjusted to properly position the wiping 50 elements relatively to upper-carrying molds of different heights.

60 The frame supporting the wiping jaws may comprise a plate 40 carried at the end of the rod 27; such plate being preferably provided with side walls or flanges 41 and a central block or guide 42. A cover plate 43 is mounted on the plate 40 over the flanges or side walls 41 of the same, and may be secured to said flanges by bolts 41^a. In the space between these flanges 65 and the cover plate 43, the wiping jaws and the mechanism for operating the same are placed.

65 The jaws carried by the mechanism at the left of the sectional mold, designed to operate upon the heel portion of the lasted upper, are indicated at 45 and 45^a, while those at the right, designed to act upon the toe portion of the lasted upper are indicated at 46 and 46^a. The respective sets of jaws are connected together by pivot pins 47 and 48. Each jaw carries an upwardly 70 projecting pin 49, preferably with a roller sleeve 49^a, for operative engagement with cam slots 50 in the cover plate 43 which occupies a fixed position with respect to the plate 40; the relation being such that when the jaws are reciprocated 75

longitudinally with respect to each cover plate of the respective frames when the latter are in the position illustrated in Figs. 3 and 5, they will rock or swing on their pivot pins 47 and 48, respectively, to effect the desired wiping action. To effect reciprocation of the wiping jaws, I provide sliding members 51 which move in the space between the plate 40 and the cover plate 43; such members 51 being adjustable and operatively connected to a rod 52, which is moved reciprocally in a manner hereinafter described; such rod 52 being disposed above the rod 27 and in alignment therewith.

For the purpose of moving the frames carrying the wiping elements to bring the blades or jaws of the latter into and out of operative position with respect to the mold 10, I provide hand levers 55, pivotally mounted at 56 to the base portions 22 of the respective frames; such levers being provided with pins 55^a which engage the underside of the cross-head 26 secured to the rods or shafts 27. The hand levers 55 are shown in the inoperative position in Figs. 1 and 2, and in the operative position with the wiping elements properly positioned over the lasted upper in the mold, in Figs. 3, 4 and 5. When the frames carrying the wiping elements are moved to operative position, they ride off the rollers 30, and lugs 40^a at the side of these frames engage one of the arms of the respective bell-crank levers; causing them to move on their pivotal connection and exert pull upon the springs which hold the wiping elements in contact with the mold and the lasted upper therein; the springs providing sufficient pressure and at the same time yielding to any inequalities of the surface engaged by such wiping elements.

The sliding members 51 are connected to the jaws of the respective sets of wiping elements by links 51^a; said sliding members being secured at their opposite ends to a cross member 58 to which they are connected by set screws or bolts 59; the cross member being slotted at 58^a so as to permit longitudinal adjustment of said sliding members 51 with respect to the same. The cross member has an upwardly projecting portion 60 to which the rod 52 is connected; the opposite end of said rod 52 sliding in a support 61 carried by and projecting upwardly from the rod or shaft 27. A block 62 may be carried by the rod 52; being adjustably held to the same by collars 63, secured to said rod by set screws. This block carries a pin 64, with a roller 64^a, and this roller is engaged by the arm 65 of a bell-crank lever pivotally mounted at 66 to a cross-bar 67, carried by and secured to the pair of sliding rods 25, mounted in the guide bearings or supports 24, carried by the adjustable support 23. The arm 65 of such bell-crank lever is slotted at 65^a for engagement with the roller 64^a mounted on the pin 64, carried by the block 62, and the latter may rock on the rod 52. In lieu of providing rocking blocks such as illustrated at 62; each carrying a pin 64 provided with a roller 64^a adapted to the slots 65^a formed in the arms 65 of the bell-crank levers, I may provide a collar 62^a fixed to the rod 52 and carrying a pin 64^b with a roller 64^c cooperating with the slot 65^a of said bell-crank lever 65, as illustrated in Fig. 9. The opposite end 68 of the bell-crank lever is connected by a ball and socket joint, or other universal connection 69, with an adjustable link 70, having a sleeve 71 at its opposite end slidably mounted upon a guide rod 72, supported in suitable brackets or supports 73

carried by and extending upwardly from an operating shaft 74 mounted in bearings 75 on the table 11. The sleeve portion 71 of each link 70 is elongated so as to provide sufficient bearing with the rod 72 to slide easily therein when the parts are moved by the operation of the hand levers 55. The shaft 74 is preferably square, and such shaft is arranged to be rocked by suitable means disposed below the table, including a motor. This motor may be operated at will through a foot lever, and when in action the shaft 74 is rocked by its connection 76 with such motor. Through their connection with the rod 72, by means of the links 70, the bell-crank levers are moved on their pivotal connections 66 to 15 reciprocate the rods 52 operatively connected to the sliding members 51, which in turn move the links 51^a connected to the wiping jaws, and the latter are rocked or swung on their respective pivot pins 47 and 48 to move over the projecting portion x of the upper and wipe the same down upon the insole y carried by the last. Fig. 5 shows the extreme inward position of the respective sets of wiping jaws, and their extreme inward position toward each other that is assumed 20 during a wiping operation; the roller pins carried by each of said jaws being in the extreme position at the end of the cam slots formed in the cover plates 43.

Motor means for operating the shaft 74, are 30 illustrated in Fig. 10. The motor driven shaft may be operatively connected, as by means of a crank 77, with the member 76. Such motor may be under control of a foot lever 78 for starting and stopping its operation, or it may be constantly driven and associated with clutching means under control of such foot lever. It will be understood that any driving mechanism that will serve to rock the shaft 74 is within the scope of my invention.

After the wiping operation has been completed, the hand levers 55 are operated to move the frames carrying the wiping elements away from the sectional mold and the lasted upper positioned therein, and the sectional mold may then 45 be opened and the lasted and wiped upper removed therefrom, and may be placed in another sectional mold of similar type for a rasping or roughening operation, or otherwise prepared, after which the sole may be applied and held in 50 the manner set forth in my copending applications.

The type of blades or jaws shown in the present instance are designed to wipe the projecting portion of the upper inwardly and over the insole carried by the last. When it is desired to wipe this projecting portion of the upper outwardly, I may provide wiping elements which will be arranged to drop into the space over the insole between the projecting edge portions of 60 the upper, and by reversing the position of the slots in the cover plates 43, the action of said wiping elements may be reversed so as to cause them to spread the projecting portion of the upper outwardly and over the top edge of the mold; 65 mechanism of an exactly similar character being employed to actuate the same both to the operative position relatively to the upper in the mold, as well as the actuation of the wiping elements when thus positioned.

The rollers 30 supporting the wiping element carriers 40 in the inactive position, may be of a duplex type as illustrated in Figs. 1, 3, 4 and 5, or I may employ single rollers for the respective carriers, as illustrated in Figs. 2, 6 and 8.

It will be understood that various modifications may be made in the form and arrangement of the mechanism disclosed, to which my present invention is broadly related, and such modifications are within the scope of the appended claims.

I claim:

1. In mechanism for effecting the manufacture of shoes, a sectional mold for holding a last and positioned upper in pulled over and taut condition; said upper having a portion projecting above the last and the latter carrying an insole, a plurality of wiping members, manually operated means for positioning said wiping members over the opposite ends of said mold for engagement with the upper, and motor means for actuating said wiping members when so positioned to level the projecting portion of the upper over the insole carried by the last.
2. In mechanism for effecting the manufacture of shoes, a sectional mold for holding a last and positioned upper in pulled over and taut condition; such upper having a portion projecting from the last and the latter carrying an insole, pairs of wiping members disposed at opposite ends of said mold, manually operated means for positioning said wiping members over the opposite ends of said mold; said wipers comprising toe and heel wipers in the form of pivotally connected jaws, and motor means for simultaneously actuating the several pairs of wiping members when so positioned to level the projecting portion of the upper over the insole carried by the last.
3. The combination with a mold supporting a last and a pulled over upper stretched thereon, of a member slidably movable into position over one end of said mold, a plurality of pivotally mounted wiping elements carried by said member and independently movable with respect to the same; said member having cam slots and the wiping elements having projections operatively engaged by said cam slots, manually actuated means for moving said wiping members into position over the mold, and motor means for operating said wiping elements with respect to said cam slots and over the lasted upper when so positioned.
4. The combination with a mold supporting a last and a pulled over upper stretched thereon, of a supporting member, a plurality of pivotally mounted wiping elements carried thereby and movable into position over one end of said mold; said supporting member having cam slots, pins carried by the wiping members operatively engaging said slots, manually actuated means for moving said wiping members into position over the mold, and motor means for reciprocating said wiping elements with respect to said cam slots whereby they may be moved on their pivotal connections and over the lasted upper when so positioned.
5. The combination with a mold supporting a last and a pulled over upper stretched thereon, of a supporting member manually movable into position over one end of said mold, a pair of wiping elements carried by said supporting member including pivotally mounted jaws, motor means for reciprocating said jaws with respect to the mold, and means for moving said jaws on their pivotal connections over the lasted upper during such reciprocative movement.
6. The combination with a mold supporting a last and a pulled over upper stretched thereon, of a slidable member aligned with the lon-

frame in close engagement with the mold, and motor means for reciprocating said wiping blades when the frame carrying the same is positioned over the mold.

5 12. In wiping means for lasted uppers, the combination of a mold in which said lasted upper is retained in pulled-over and taut condition, a slideable frame adapted to move with respect to the longitudinal axis of said mold; said frame having an internally disposed slideway, a pair of wiping blades disposed in said internal slideway, manual means for moving said frame over one end of the mold, springs for holding down the slideable frame whereby the wiping elements may be held in yielding contact with the mold and the lasted upper positioned therein, and motor means for reciprocating said wiping blades when positioned over the mold.

13. In wiping means for lasted uppers, the combination of a mold in which said lasted upper is retained in pulled-over and taut condition, a slideable frame adapted to move with respect to the longitudinal axis of said mold; said frame having an internally disposed slideway, a pair of wiping blades disposed in said internal slideway, manual means for moving said frame over one end of the mold, springs for holding down the slideable frame whereby the wiping elements may be held in yielding contact with the mold and the lasted upper positioned therein, bell-crank levers to which said springs are connected, means carried by the slideable frame for actuating said levers when the wiping elements are positioned over the mold, and motor means for reciprocating said wiping blades when positioned over the mold.

14. In wiping means for pulled-over and lasted uppers, the combination of a mold in which a lasted-upper is retained in pulled-over and taut condition, a sliding frame, a pair of wiping blades supported in said sliding frame, manual means for moving said sliding frame to position the same over one end of the mold, means for holding said sliding frame in close engagement with the mold, means for imparting reciprocable movement to said wiping blades with respect to the frame; such means including a bell-crank lever, and motor means for operating said bell-crank lever.

50 15. In wiping means for lasted uppers, a slideing frame supporting a pair of wiping jaws, means for imparting movement to said jaws with respect to the frame including a bell-crank lever, a rock-shaft, a motor for operating the same, a guide rod supported by said rock-shaft, and means for operating said bell-crank lever comprising a link slidably mounted on said guide rod and connected at its opposite end to the bell-crank lever.

60 16. In wiping means for lasted uppers, a slideing frame supporting a pair of wiping jaws, means for imparting movement to said jaws with respect to the frame including a bell-crank lever, means for operating said bell-crank lever, a rock

shaft, a motor for operating said rock shaft, a guide rod supported by said rock shaft, a link slidably mounted on said guide rod, and a universal joint connecting the opposite end of said link to said bell-crank lever.

5 17. In wiping means for pulled over and lasted uppers, a slideable frame, means for positioning said frame over the lasted upper, a pair of wiping blades mounted in said frame, means slideable with respect to said frame for bodily moving 10 said blades, means carried by the slideable frame for rocking said blades, and an adjustable support for said slideable frame and the blade-operating means.

18. In wiping means for pulled-over and lasted 15 uppers, the combination of a mold in which a pulled-over and lasted upper is mounted, a slideable frame, manually actuated means for positioning said frame over the lasted upper positioned in the mold, a pair of wiping blades carried 20 by said frame, means for actuating said wiping blades when positioned over the mold, a rod carrying said slideable frame, a sliding cross-head to which said rod is connected, and a loose connection between said rod and the cross-head. 25

19. In wiping means for lasted uppers, a slideable frame, a pair of wiping jaws carried by the same, a rod carrying said slideable frame, a cross-head, a series of slideable rods supporting said cross-head; the rod carrying the slideable frame being loosely mounted with respect to said cross-head, a supporting rod in line with the rod supporting the slideable member and arranged above the same, a member slideably mounted with respect to the slideable frame and connected to said supporting rod, and means operatively connecting said last-mentioned member with the wiping jaws; said last-mentioned member being independently operable so as to actuate 30 said jaws after the slideable frame has been positioned over the sectional mold. 35

20. In a structure such as set forth in claim 19, an adjustable connection between the slideable member and the wiping jaws whereby the extent of the independent reciprocatory movements of 40 said wiping jaws may be adjusted with respect to the size of upper mounted in the sectional mold.

21. In wiping means for pulled over and lasted uppers, a pair of wiping blades, a support for the 50 same including a plate with cam slots, a slideable member, pins carried by the respective blades and adapted to ride in said cam slots, links connecting said slideable member and the wiping blades whereby movement of said slideable member is imparted to the wiping blades; the cam slots of said plate causing said blades to move on their pivots toward and from each other when the links are reciprocated by the slideable member, a bell-crank lever connected to said slideing 55 member, and motor-actuated means for operating said bell-crank lever. 60

JOHN M. ROHRER.
